(57) **CLAIM**

I claim the ornamental design for a shoe box, as shown and described.

DESCRIPTION

FIG. 1 is a perspective view of a shoe box showing my new design;

FIG. 2 is an end elevation view of the shoe box;

FIG. 3 is the opposite end elevation view of the shoe box;

FIG. 4 is a side elevation view of the shoe box;

FIG. 5 is an elevation view of the other side of the shoe box;

FIG. 6 is a top plan view of the shoe box; and,

FIG. 7 is a bottom plan view of the shoe box.
